PRINTING MECHANISM

George F. Daly, West Orange, N. J., assignor to
International Business Machines Corporation,
New York, N. Y., a corporation of New York

Application November 13, 1935, Serial No. 49,480

4 Claims. (Cl. 101—93)

This application is a continuation in part of the application Serial No. 496,437, filed November 18, 1930.

The principal object of the invention is to provide selective control mechanism for a printing tabulator whereby selected characters may be printed in response to the analysis of an arbitrary arrangement of perforations in a record card.

A more specific object of the invention is to provide record cards, each having a series of perforations arranged to transmit a series of differently timed impulses and selective means for utilizing one or more of the timed impulses to control printing mechanism.

15 In certain classes of work where dates or the like are to be printed under control of record cards, it has been necessary to effect perforations representing the dates to be printed, on the record cards. If these cards later are to be utilized 20 in preparing other reports in which the perforated date is not desired, but some other date is required, it has been necessary to re-perforate the cards in another field with the new date, or, if space is not available on the card, to dispense 25 with such printing. In accordance with the present invention, it is proposed to set aside a field of all record cards from which dates are to be printed and in such field to arbitrarily punch a hole representing "1" in the first column, "2" in the second column, "3" in the third column, and so on, up to "9". These fields as they feed through the machine are analyzed and circuits potentially established by the holes in the card columns at 30 times represented by the location of the perforations in the several columns.

If, for example, it is desired to have the record card print a predetermined date, such as 6-29, representing June 29th, the columns containing the 6, 2, and 9 perforations are manually selected 40 to complete circuits at such times to energize printing magnets which in turn position type bars to print 6-29. If the same card is to be utilized in connection with some other report to print, for example, the number 15558, a further manual 45 selection in the columns containing the 1, 5, and 8 perforations is made to cause these columns to control the positioning of the type bars to select the number for printing.

In accordance with a modified form of the 50 invention a commutator device is provided which is arranged to close circuits at successive times in the same manner as the series of perforations in the record cards, thus making the utilization of the separate punched field unnecessary.

55 Various other objects and advantages of the

invention will be obvious from the following particular description of one form of mechanism embodying the invention or from an inspection of the accompanying drawings; and the invention also constitutes certain new and useful features 5 of construction and combination of parts herein-after set forth and claimed.

In the drawings:

Fig. 1 represents the printing circuits of the tabulating machine involved in the operation of 10 the invention.

Fig. 2 is a similar view showing the arrangement according to the modified form of the invention.

Fig. 3 is a representation of the printing mechanism.

Fig. 4 is a specimen of a fragment of a record card having a field perforated for carrying out the objects of the invention.

The general arrangement of the machine is 20 substantially as disclosed in the patent to Daly and Page, No. 1,762,145, to which reference may be made for details of construction and operation of the parts of the machine with which the present invention is not specifically concerned. In 25 such machines, record cards, as in Fig. 4, are successively moved to pass a row of analyzing brushes so that the index point positions 9, 8, 7, etc. are sensed by the brushes, in succession. As the cards move past the brushes, printing type 30 bars 10 (Fig. 3) move upwardly to pass printing position opposite platen 11 as the card passes the brushes and the timing is such that the "9" type element 12 is at printing position as the "9" index point position is at the brushes and the other type 35 elements 12 will be at the printing position as the correspondingly numbered index point positions of the card are at the sensing brushes. As any position containing a perforation is sensed by the brushes, a circuit will be completed to printing 40 magnet 13 which, upon energization, will attract its armature 14 to rock a latch 15, thereby releasing stopping pawl 16 for engagement with one of the teeth 17 of the type bar 10, to interrupt the 45 type bar with the type element 12 corresponding to the perforation sensed, at the printing line.

The type bars are carried by a crosshead 18 mounted for vertical reciprocation on rods 19 and are urged upwardly by spring-operated levers 19 50 pivoted to the crosshead so that upon interruption of movement of a type bar, the crosshead will continue to move upwardly and lever 19 will yield to permit the type bar to remain in its adjusted position.

The crosshead is operated by a cam 20 through operating levers, generally designated 21.

In Fig. 1, the analyzing brushes are designated LB and they cooperate with a common contact roller 22 which has electrical connection with the brushes 23 of an impulse distributor 24, whose segments bridge the contacts 23 as the index point positions of the card are at the brushes. The brushes 23 are further connected through 10 lower card lever contacts LCL to one side of line 25. The contacts LCL are closed during the period the card is passing the brushes. In the circuit are also shown print magnets 13 which are connected through a commutator 26 and cam contacts 27 to the left side of line 28. The record card (Fig. 4) is provided with a field comprising nine columns, which field is designated 29. The columns are numbered 1 to 9 and a series of perforations as indicated is made in which the 15 first column has a perforation in the "1" index point position, the second column a perforation in the "2" index point position, and so on. The brushes which traverse these nine columns are indicated in Fig. 1 by the numerals 1 to 9 and 20 as the field 29 passes these brushes, contact will be made therethrough in successive order. The brushes LB are provided with multiple plug sockets 30 from which plug connections 31 may 25 be made to plug sockets 32 wired to the printing magnets 13. Thus, for example, if a plug connection is made from the "2" brush socket 30, to one of the sockets 32, a circuit would be completed from the "2" perforation analyzed to energize the magnet 13 at such time and interrupt its 30 related type bar with the "2" type element in 35 printing position. Similar connections to the other sockets 30 will cause energization of the magnets 13 at times depending upon the brush LB to which connection has been made.

40 In Fig. 1 are shown three connections for controlling the printing of the date June 29th for which a connection 31 is made from the 2, 6, and 9 sockets 30 to three adjacent sockets 32 and as the field passes the brushes, the selected type bars will be positioned to print 6-29.

In Fig. 2 is shown a modified form of the invention in which a commutator 33 having conducting segments 34 electrically connected to a common ring 35 receive current from a brush 36 45 connected to the brushes 23. The segments 34 are arranged and timed to contact the brushes 37 at the same time that the correspondingly numbered index point positions are encountered by the brushes LB and it will be appreciated that 50 the circuits completed will be similar to those explained in connection with Fig. 1. In Fig. 2 are shown plug connections 31 for printing the number 15558 in which use of the multiple plug sockets 30 enables the "5" brush 37 to complete 55 three parallel circuits to position three adjacent type bars with the "5" type element in printing position.

While there has been shown and described and pointed out the fundamental novel features of

the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described, a plurality of type carriers, means for moving the same to printing position, and means for causing the selective positioning of said carriers in the same manner for each operation to repeatedly print a number, said last named means comprising a plurality of magnets, one for each carrier, a series of contacts, one for each digit, plug connections between said magnets and the contacts arranged in accordance with the number to be repeatedly printed and a commutator for completing circuits through said contacts in succession for each operation of the carriers. 10
2. In a machine of the class described, a plurality of type carriers, means for moving the same to printing position, and means for causing the selective positioning of said carriers in the same manner for each operation to repeatedly print a number, said last named means comprising a plurality of magnets, one for each carrier, a series of contacts, one for each digit, plug connections 15 between said magnets and the contacts arranged in accordance with the number to be repeatedly printed and including circuit closing means for completing circuits through said contacts in succession for each operation of the carriers. 20
3. In a machine of the class described, a plurality of type carriers, means for moving the same to printing position and means for causing the selective positioning of said carriers in the same manner for each operation to repeatedly print 25 a number, said last named means comprising a plurality of magnets one for each carrier, a series of contacts, one for each digit, circuit connections between said magnets and the contacts arranged in accordance with the number to be repeatedly 30 printed and including circuit closing means for completing circuits through said contacts in succession for each operation of the carriers. 35
4. In a machine of the class described, a plurality of type carriers, means for moving the same to printing position and means for causing the selective positioning of said carriers in the same manner for each operation to repeatedly print 40 a number, said last named means comprising a plurality of magnets one for each carrier, a series of contacts, one for each digit, circuit connections between said magnets and the contacts arranged in accordance with the number to be repeatedly 45 printed and including circuit closing means for completing circuits through said contacts in succession for each operation of the carriers. 50
5. In a machine of the class described, a plurality of type carriers, means for moving the same to printing position and means for causing the selective positioning of said carriers in the same manner for each operation to repeatedly print 55 a number, said last named means comprising a plurality of controlling devices, one for each carrier, a series of control elements, one for each digit, connections between said controlling devices and said control elements arranged in accordance with the number to be repeatedly 60 printed and including means for causing said control elements to render said controlling devices effective through said connections in succession for each operation of the carriers. 65
